UNITED STATES PATENT OFFICE.

HARRY E. KERR, OF CLEVELAND, OHIO, ASSIGNOR TO THE CLEVELAND GAS BURNER & APPLIANCE COMPANY, OF CLEVELAND, OHIO, A CORPORATION OF OHIO.

GAS-BURNER UNIT FOR HEATERS.

Application filed December 3, 1924. Serial No. 753,618.

To all whom it may concern:

Be it known that I, HARRY E. KERR, a citizen of the United States, residing at Cleveland, in the county of Cuyahoga and State of Ohio, have invented certain new and useful Improvements in a Gas-Burner Unit for Heaters, of which the following is a specification.

My invention relates to an improvement in a combined burner, base and drip pan for water heaters, such as coil tank heaters and also instantaneous heaters in which gas burners are used to heat copper coils and water passing through the coils, or other surfaces or sections containing water, and my object in general is to provide a single unit adapted to function as a base or closure member for the bottom of the heater, and as a gas burner and also a drip pan, or condensation collector, thereby making a more compact and lighter heater structure than heretofore provided, reducing the cost of manufacture as compared with old practices, and simplifying the matter of assembly and union of the parts, while also definitely fixing and establishing the working relation of the gas burner and drip pan to the water heating coils or surfaces or sections containing water to be heated, thus obtaining the very best results in operating heaters of various sizes and diameters. A certain amount of condensation and drippage occurs in such heaters when water is circulating and heat is applied to the coils or sections especially during initial operations when cold water is passing through the coils or sections, and one object of this invention is to prevent this drippage from escaping and to collect it in close proximity to the flame where it may be rapidly evaporated and carried away without affecting the operation of the gas burner. The drippage or condensation has corrosive or deteriorating properties, particularly on cast or sheet iron, but by collecting and quickly dissipating the drippage certain objectionable results in the use of such heaters are overcome. The present invention is an improvement in the gas burner shown in my application, Serial No. 720,558, filed June 17, 1924, in which a series of jets are particularly arranged and

for commingling and burning air and gas in various forms and classes of hot water heaters and boilers whether controlled by hand or automatically.

In the accompanying drawings, Fig 1 is a sectional view of the lower part of a coil tank water heater embodying my combined burner, base and drip pan, which is shown partly in section and partly in side elevation. Fig. 2 is a vertical section of the heater body and base unit on line 2—2 of Fig. 3, and Fig. 3 is a top view of the base unit alone. Fig. 4 is a vertical section of the unit on line 4—4 of Fig. 3. Fig. 5 is a sectional view of a jet. Fig. 6 is a top view corresponding to Fig. 3 of a base unit embodying a smaller gas burner having a closely grouped set of jets, and Fig. 7 is a vertical section thereof.

As exemplified in the drawings, a single unit A is adapted to serve as a base and closure member for the heater shelf or body B, as a gas burner, and as a drip collector and evaporator. Body B is usually made in two halves or sections hinged together, the swinging half serving as a door, and the stationary section 2 supports a single or multiple coil 3 of copper pipe in the major portion of its length. The body sections may contain air intake openings at their lower ends, or these openings may be dispensed with, especially if unit A is provided with openings 4 in its pan 5 or a central opening 6 as shown. Unit A is a single casting comprising a horizontal wall 7 having an annular skirt or depending flange 8 and upwardly projecting lugs or a rib 9 at its perimeter. Stationary shell section 2 is seated upon wall 7 and held by lugs or ribs 2 in a concentric position in respect to unit A as a whole, and these parts may be fastened rigidly but detachably together by screws or bolts 10 extending through an inturned flange or ears 11 on shell 2. The upper central part of unit A may be elevated above wall 7 and cast in the form of a hollow ring 14 having round or straight side walls, and a series of bosses or protuberances 15 extend upwardly from the top of this ring at uniformly spaced intervals in the circle, the number thereof depending upon the size and diameter of the heater.

and burner. Each protuberance 15 has a pair of flattened faces 16-16 disposed at right angles or quartered in respect to each other and also sloping upwardly at an angle of approximately forty-five degrees to permit a pair of brass jets or nipples 17-17 to be projected upwardly at that angle toward similar jets or nipples mounted on the adjoining bosses or protuberances 15. To 10 that end the slanting faces on the successive bosses or protuberances are drilled at right angles and screw-threaded to receive the reduced screw-threaded ends of the jets 17, which have axial gas orifices and lateral air 15 intake openings in their base portions communicating with an elongated discharge bore in the main body of the jet or nipple. These jets or nipples are of a predetermined length and situated far enough apart in pairs to 20 cause the streams of gas and air issuing therefrom to impinge and come into confluence a substantial distance above the wall and ring when the flow of gas and pressure are sufficient to bring about a meeting of 25 the streams. Otherwise a separate flame blue green in color is maintained at the mouth of each jet and the present burner functions so well that the gas may be cut off nearly in its entirety, or the gas pressure 30 reduced to the burner to 1/50 of an inch water pressure and still permit a small bead of blue flame to exist at the mouth of each jet. When turned on, the converging streams of gas and air will produce a column 35 of green or blue-orange flame of substantial height centrally between each pair of converging jets. The burning of the gas, either high or low, is protected by annular skirt 8 and the other walls of the unit, and the 40 central part of wall 7 lies in a lower plane than the top of ring 14 and serves as a protecting diaphragm and also as a drip pan centrally within the burner. A small circular air intake opening 6 is provided at 45 the center of the diaphragm and gas-distributing ring, and other openings 4 may also be provided opposite bosses 15 to admit a restricted amount of air to the group of jets and the central part of the heater. The 50 border edge 19 of opening 6 and any other air opening which may be used, is beaded or flanged upwardly more or less to provide a shallow water collecting and evaporating 55 space within higher ring 14. An intake pipe or extension 21 is cast integral with the gas ring and top wall 7 and this intake may extend laterally through skirt 8 as shown in Fig. 1, or it may be projected above the top of wall 7 as shown in Figs. 60 6 and 7, and pass through suitable openings formed in the meeting edges of the stationary and hinged body sections of the heater. Any suitable gas valve and gas controlling or regulating device may be used for the 65 unit, but as such devices form no part of this invention none are shown herein. However in some instances it is desirable to have a gas intake pipe connect with the base unit without passing through an opening in the body or shell, and in Fig. 1, I show the 70 hollow gas ring as depressed and lying below the top of the unit to permit the stationary part 2 of the body or shell to be seated on the elevated border part 23. The intake extension 21 lies wholly beneath 75 border seat 23 and its mouth end extends through skirt 8. An annular recess 24 may also be formed between border seat 23 and hollow ring 14 to serve as an additional drip receiving chamber outside of the gas 80 ring. In Fig. 3 a series of air openings 4 are shown in the drip pan adjacent each boss 15 and intermediate the base ends of the gas jets, and in Fig. 6 similar openings 4' are formed in wall 7' outside of said 85 bosses.

In Figs. 5 and 6, I show a combined base burner and drip pan corresponding to that shown in the other views but having a gas-distributing ring 14' cast integral and 90 raised entirely above the top wall 7'. This unit also has a skirt 8' and a central drip pan 5', but the ring is relatively smaller than the ring in Fig. 1. Consequently in order that the efficiency of this smaller 95 burner be as great as the larger one I use the same number of pairs of gas jets as in the other case but relate them in a different way to permit each co-operating pair to function without interference with the 100 others. Thus, as shown, I mount three pairs of inclined gas jets 17' on three protuberances 15' spaced uniformly apart on the ring, and mount an additional pair of inclined jets 25 radially of the ring on other 105 flattened faces or protuberances 26. The base ends of the radial jets 25 may be located beneath the mouth ends of one of the other pair of inclined jets and the separate streams of gas and air delivered from the separate 110 pairs of jets will not interfere with each other or affect combustion and separate burning of the gas streams directed into confluence from the opposed mouths of the jets. 115

The advantages of the present invention will be understood by reference to the following: Tank heaters, sometimes referred to as coil heaters, side arm heaters or instantaneous heaters, are used to heat water 120 passing through their coils into a range boiler or tank. The complete combination, when connected together so that the water will circulate from the heater to the tank, is called a tank heater. Such tank heaters 125 are made with single, double and triple coils in various sizes and the shells or casings of the heaters range in diameter from about six inches to twelve inches or more, depending upon the capacity of the tank. Similar 130

tank heaters also form a part of a large percentage of so-called automatic storage heaters. In some cases the lower or bottom part of the casing of the tank heaters is made with a base flange or skirt, and in other instances without a skirt. It has also been customary to provide a separate condensation pan for such heaters, and to fasten the burner, usually a gas burner having a Bunsen mixer, within this separate pan. The pan is used to collect condensation, but independently or apart from the burner. In some heaters the gas is fed to the burner from the side of the heater and some from the bottom, and the burners usually have mixers which extend a distance of 3" to 6" from the face or end of the mixer to the part of the burner which is provided with the gas orifices, and the gas and air are assumed to be properly mixed in passing through this length of mixer. In the present improvement the mixer is eliminated which reduces the weight, and the present improvement also does away with a heavy burner made of several parts and a separate pan to collect condensation. As constructed, the present burner permits introduction of air for combustion through the center or in other places of advantage in the burner itself, and also promotes quicker evaporation of condensation as the pan is an integral part of the burner and situated contiguous to and near the flame. In that connection it should be understood that such condensation has a powerful destructive effect on iron and that it is especially desirable that the collected liquid be evaporated rapidly and carried away with the flames. By making the pan an integral part of the burner the weight and height of the heater may be reduced at its lower end, and such a burner unit permits quicker assembly and attachment. It is also less bulky and requires a smaller shipping crate, and there is less shipping breakage, and where replacements are to be made the replacement costs and labor are greatly reduced. The compact construction of the unit also permits it to be cast of aluminum without prohibitive cost, thus reducing the weight to a minimum, and there is the added advantage that aluminum will not be affected detrimentally by the drippage. The unit shown in Figs. 6 and 7 contains all the advantages enumerated, and in addition the special arrangement of jets concentrates a large volume of heat in a small area and permits the making of a smaller burner than the other without loss in efficiency. In both units, the jet construction and design and the arrangement of the jets in pairs, is important in applying and directing the flame to the coils in a proper way to develop high heating efficiency, and the compact arrange-

ment of all the parts in a single unit with the jets mounted as shown contributes still further to that desirable result.

What I claim, is:

1. A cast metal base unit for a heater casing containing water circulating elements, consisting of a base member, gas burner, and drip pan formed in a single piece and having air and gas commingling tubes mounted thereon. 65
2. An attachment unit for a heater casing, consisting of a gas burner having a drip collecting and evaporating pan formed integrally therewith in the top thereof and having a raised seat at its border for said casing. 75
3. A bottom unit for a cylindrical heater casing containing water circulating elements, consisting of a hollow gas burner having pairs of reversely-inclined tubular jets at its top having small air intake openings at their lower ends and adapted to bring separate streams of gas and air into confluence, and an integral collecting and evaporating pan with air openings opposite the air openings in the lower end of said tubular jets. 85
4. A unitary base attachment for a heater casing containing water circulating elements, comprising a gas burner having an integral evaporating pan for collecting drippage from said elements and provided with integral means at its border adapted to permit said unit to be detachably connected to the lower part of said heater casing. 95
5. A base unit for a heater casing containing water circulating elements, comprising an annular gas burner having a shallow drip pan cast integrally therewith at its center and formed with an integral annular seat for said casing concentric with said annular burner. 100
6. A unitary gas burner, drip pan, and a skirted base cast in one piece and adapted to be detachably affixed to the bottom of a heater casing containing water circulating elements. 110
7. A cast metal unit for a heater casing, comprising a circular gas-distributing body having an integral skirt and an integral diaphragm with air openings, and separate pairs of tubular gas jets having small air intake openings at their lower ends and set in inclined converging relation upon the top of said burner said diaphragm lying in a lower plane than the top of said burner and said air openings in said diaphragm being located close to the air openings in the lower ends of said tubular jets. 115
8. A base unit for a heater casing, comprising a skirted body having a depressed central portion, a hollow gas distributing chamber formed with inclined walls at its 120

- 1 top, a series of tubular gas jets having small air intake openings at their lower ends and being mounted in pairs in reversely-inclined position upon said inclined walls, and air 5 openings, arranged in said central opening close to the air openings in the lower ends of said tubular jets and around a central air opening therein.
- 2 9. A base unit for a heater casing, comprising a circular gas burner having a central opening, and an integral border adapted to seat said casing, an annular skirt integral with and depending from said integral border, and a series of commingling tubes 10 mounted in pairs in reversely-inclined position upon the top of said burner inwardly from said border.
- 3 10. A base unit for a heater casing, comprising a gas distributing body having flattened bosses at its top, said body having an integral outwardly-extending flange having centering projections for said casing, and separate pairs of reversely-inclined commingling tubes mounted upon said flattened 15 bosses.
- 4 11. A base unit for a heater casing, comprising a gas distributing body having an integral raised border seat for said casing, and an integral skirt depending annularly 20 from said seat, and an integral gas intake extension extending through said skirt beneath said seat, in combination with separate pairs 25
- 5 of reversely-inclined commingling tubes mounted upon said body.
- 6 12. A base unit for a heater casing, comprising a circular gas distributing body having an integral drip pan at its center provided with beaded air openings, the top border portion of said unit having vertical projections and means to permit the unit 30 to be affixed centrally to the lower end of said casing, and separate pairs of tubular gas jets having small intake openings at their lower ends and mounted upon said body at spaced intervals in inclined relation adapted to produce vertical columns of flame above and around said drip pan, said air openings in the pan being arranged close to said air openings in the lower end of 35 said tubular jets.
- 7 13. A combined base unit and gas burner for a water heater, comprising a hollow ring-shaped body having an integral perforated diaphragm at its center and an integral seating portion for a casing annularly 40 around the hollow body and an integral skirt depending from said seating portion, said body having a plurality of pairs of co-operating commingling tubes extending therefrom, including a pair of such tubes 45 extending diametrically of said body and diaphragm.

In testimony whereof I affix my signature.
HARRY E. KERR.
